UNITED STATES PATENT OFFICE

HAROLD B. LITTLE, OF BALTIMORE, MARYLAND, ASSIGNOR TO THE BALTIMORE
ENAMEL & NOVELTY CO., OF BALTIMORE, MARYLAND

SIGN FRAME

Application filed July 29, 1932. Serial No. 625,915.

This invention relates to signs, and particularly to such signs as are suspended from a suitable hanger, or are supported upon a pedestal, or standard.

- 6 These signs usually include a sign plate, a rim surrounding the same, and means for holding the rim securely in position on the sign, and it is the principal object of this invention to provide a structure of this nature
10 which will be rigid, but may be easily and quickly disassembled for the removal and replacement of the sign plate.

Other objects and advantages will be apparent from the following description when taken in connection with the accompanying drawing.

In the drawing:

Figure 1 is an elevation of a sign, made in accordance with the present invention, the 20 same being shown supported on a standard.

Figure 2 is an enlarged transverse sectional view on the line 2—2 of Figure 1.

Figure 3 is a vertical sectional view on the line 3—3 of Figure 2.

25 Figure 4 is a side elevation showing the invention used in connection with a rectangular frame.

Figure 5 is a sectional view through the form shown in Figure 4.

30 Figure 6 is a plan view of the support, the sign plate and rim being removed.

Referring to the accompanying drawing, 10 represents the rim portion of the sign frame, which is in the form of a split ring, and has a longitudinal channel 11, in its inner face, defined by the parallel ribs 12, said channel being adapted to receive the marginal edge of a sign plate 13. The marginal edges of the rim, outwardly of the ribs, 25 constitute the circumferentially extending flanges 14. On the outer face of the rim, at opposite sides of the split, are secured the outwardly extending lugs 15 and 16, which may be attached to the rim ends by welding, 40 or otherwise, or which may be formed thereon by manipulating the material of which the rim is constructed.

The support for the sign plate and rim, which holds the latter tightly in position on 45 the former, comprises a block 17 which may

be formed for attachment to a standard 18, illustrated in Figure 1, whereby the sign may be held in upright position, as will be understood in connection with signs of this character. Formed on opposite vertical sides of 55 the block 17, and extending beyond both ends thereof, are the wings 19, which may be shaped to conform with the contour of the sign plate, as illustrated.

On the inner side of each of the said wings 60 there is formed an inturned, longitudinally extending, marginal flange 20, beneath which is adapted to be engaged one of the side flanges 14, of the rim 10.

One end of the block 17 is extended above 65 its upper face 21, to form a flange 22, which is connected, at its ends, to the wings 19. This flange is to be engaged by the lug 16, of the rim, as clearly shown in Figure 3.

Connecting the intermediate portions of 70 the wings 19, above the block, is a transverse bar 19', and formed centrally and longitudinally through the block 17 is an opening 23. Removably engaged against the unflanged end of the block is a plate 24, having 75 an opening 25, adapted to register with the opening 23, and disposed through these openings of the plate and block, is a bolt 26, having a nut 27, for holding the plate in position.

80 It will be noted that the plate 24 extends above the block 17 to a distance approximately equal to the height of the flange 22, and that it engages with the lug 15, of the rim.

To assemble the device, the lug 16 is hooked 85 over the flange 22, and the rim is then brought into position with the adjacent portions of its flanges 14 in engagement with the inturned flanges 20, of the wings 19. The end 90 of the rim, carrying the lug 15, is then sprung to a slight degree, and the sign plate placed in position with its edge seated within the channel 11, after which the said end of the rim is brought back into position with the lug in close proximity to the lug 16. The plate 24 is then placed in position on the block with its upper end in engagement with the lug 15, and drawn tight by means of the bolt 23, which tightening movement causes 95 100 106

the rim to snugly embrace the sign plate, and to be firmly held upon the support. When the parts have been thus assembled, the support may be screwed, or otherwise attached 5 to the pedestal or standard 18, or may be suitably suspended from a hanger, according to conditions.

When a rectangular sign is to be used, the supporting means shown in Figures 4, and 10 5, is employed, said means being formed along the same general lines as that already described, with slight modifications in the outline thereof, so that the supporting means will conform with the corner of 15 the rim surrounding the sign plate. This form is especially adapted for use in connection with suspended or hanging signs.

In the form shown in Figures 4 and 5, the rim 28 has the same cross section as that 20 already described, being provided with the channel 29, for the periphery of the sign plate 30, and the marginal flanges 31, together with the lugs 32 and 33, on the outer 25 faces of the respective ends thereof.

25 The supporting means, used in connection with the form illustrated in Figures 4, and 5, comprises a hollow block 34, which includes the arcuate wall 35, the end portions 36 and 37, of which, are directed inwardly 30 to lie at right angles to each other, the former end portion being of slightly greater length than the latter, for a purpose that will be obvious from the description to follow. Formed through the end portion 37 is 35 a threaded opening 38.

On each side of the block 34 is an integral wing 39, corresponding to the wings 19, the ends of which wings 39 project beyond the ends of the block, and formed longitudinally 40 on the inner face of each of these wings is an inturned flange 40, corresponding with, and performing the same function as the flanges 20.

Disposed against the inturned end 37, of 45 the block, is a plate 43, provided with an opening 42, which registers with the opening 38, a screw 44 being engaged through the opening 42, and threaded into the opening 38, for holding the said plate in proper 50 position, and for drawing the rim.

The assembling of this form of the invention is practically the same as that described in connection with the first form referred to, as will be clearly understood, the lug 32 being hooked over the end portion 36, and the lug 33 being held by the plate 43.

The rectangular frame will usually be made in two sections, one of which will surround three sides of the sign plate, and the 60 other the remaining side, usually the top. Two of the supporting devices, as illustrated in Figures 4 and 5, will then be employed, one at each point where the rim ends join.

In the case of very large signs, it may be 65 found advisable to construct the rim in four

sections, one for each side of the plate, and to use four of the supports, one at each of the rim joints.

What is claimed is:

1. A sign construction including a sign plate, a rim surrounding the plate, and a support for the rim, said support having integrally connected parts engaging opposite sides of the rim for holding the same, and means connected thereto for contracting the rim into engagement with the plate. 70

2. A sign construction including a sign plate, a rim surrounding the plate, and a support for the rim, said rim support having means overlying the rim edges for holding the rim, and having means secured thereto for contracting the rim into firm engagement with the plate. 80

3. A sign construction including a sign plate, a split rim surrounding the plate, and a support for the rim, said support having parts engaging the rim, for holding the same, means fixed to the support for securing a rim end, and means adjustably connected to the support for securing a rim end. 85

4. A sign construction including a sign plate, a split rim surrounding the plate, lugs on the rim, and a support for the rim, said support including a base, means on the base for holding the rim, fixed means on the base engaging one of said lugs, and adjustable means on the base engaging the other of said lugs. 90

5. A sign construction including a sign plate, a split rim surrounding the plate, lugs on the rim, and a support for the rim, said support including a base, flanges connected to the base and overlying the rim, a flange on the base in engagement with a lug, and a member adjustably connected with the base in engagement with a lug. 100

6. A sign construction including a sign plate, a split rim surrounding the plate, lugs on the rim, and a support for the rim, said support including a base, flanges connected to the base and overlying the rim, a flange on the base in engagement with a lug, a member adjustably connected with the base in engagement with a lug, and means for connecting the base to a support. 110

7. A sign construction including a sign plate, a split rim surrounding the plate, lugs on the rim, and a support for the rim, said support including a base, holding means secured to the base and overlying the rim, a flange on the base in engagement with a lug, a movable plate in engagement with a lug, and a screw passing through the plate and carried by the base for adjusting the plate. 120

8. In a sign construction, the combination with a sign supporting rim having side flanges and terminal lugs, of a support for said rim including a base, flanges carried by the base, and overlying the rim flanges, means integral with the base for engagement by a 125

rim lug, movable means on the base for engagement by a rim lug, and means for moving said movable means to contract the rim.

9. A sign construction including a sign plate, a contractible rim surrounding the plate, and means for supporting the rim, said rim supporting means including a base having fixed means for holding one end of the rim, adjustable means for holding the other end of the rim, and means for adjusting said adjustable means to contract the rim.

In testimony whereof, I affix my signature.

HAROLD B. LITTLE.
